Primary Examiner — Rosemary K Tarcza*Assistant Examiner* — James Thorn, Sr.(74) *Attorney, Agent, or Firm* — Fraser Clemens Martin & Miller LLC; Michael E. Dockins(57) **CLAIM**

The ornamental design for a juicer, as shown and described.

DESCRIPTION

FIG. 1 is a perspective view of a juicer incorporating the features of the invention;

FIG. 2 is a front elevational view of the juicer of FIG. 1;

FIG. 3 is a rear elevational view thereof;

FIG. 4 is a top plan view thereof;

FIG. 5 is bottom plan view thereof;

FIG. 6 is a right side view thereof; and,

FIG. 7 is a left side view thereof.

The ornamental design which is claimed is shown in solid lines in the drawings. The broken lines shown in the drawings are for the purpose of illustrating environmental structure and form no part of the claimed design.

1 Claim, 4 Drawing Sheets(56)
